It is certified that error appears in the above-identified patent and that said Letters Patent is hereby corrected as shown below:

On the Title Page

Description should read:

FIG. 1 is a perspective view of a probe showing my new design;
FIG. 2 is a front view thereof, the rear view being a mirror image thereof;
FIG. 3 is a left side view thereof;
FIG. 4 is a right side view thereof;
FIG. 5 is a top plan view thereof; and
FIG. 6 is a bottom plan side view thereof.

The broken lines show portions of the probe that form no part of the claimed design. The drawings include surface shading which represents contour and not surface ornamentation.

The parallel dash-dot-dash broken lines represent a symbolic break and form no part of the claimed design.
